FIRING MECHANISM FOR AUTOMATIC GUNS

Josef Vesely, Hoddesdon, England

Application March 4, 1942, Serial No. 433,322
In Great Britain June 10, 1941

2 Claims. (Cl. 42—3)

The present invention relates to improvements in sub-machine guns of the dynamic type and particularly in the firing mechanisms of such guns.

Guns of the so-called "dynamic type" are guns in which the breech block is slidably mounted in the gun body and in which no positive locking means are provided for maintaining the breech block in the firing position, retention of the breech block in the firing position being dependent upon its inherent kinetic energy and the pressure of the recoil spring.

A principal object of the invention is to provide an improved firing mechanism which, in combination with a gun employing a breech block of the dynamic type, serves positively to prevent premature firing of the cartridge but fires the cartridge at the proper moment, and makes use of the kinetic energy of the forwardly moving breech block both for firing the cartridge and for absorbing surplus recoil energy.

This and other objects are accomplished according to the present invention by the arrangement and combination of parts set forth in the following detailed description, defined in the appended claims and illustratively exemplified in the accompanying drawings in which:

Figure 1 is a sectional side elevational view of the gun which has been chosen for illustrating the invention;

Figure 2 is a sectional side view of a part of the gun on a larger scale and showing the positions of operative parts as the forward movement of the breech approaches completion;

Figure 3 is a view similar to Figure 2, but showing the positions of the same operative parts immediately after firing a round;

Referring to the drawings, the gun comprises a barrel 1 surrounded by a cooling jacket 2, this barrel being rigidly connected with a gun body 3 which is of circular form in cross-section. The usual rearsight 4 is secured to the generally cylindrical gun body or casing 3 and provision is made in the lower part of the gun body for attaching a magazine 5 of any suitable design. For example, a holder 6 may be provided for this purpose at the lower side of the gun body 3, to receive the magazine 5 which is held in the holder 6 by a suitable catch 7.

The gun body is rigidly but removably connected at its rear end to a butt holder 8 which is in turn connected with a butt 9 of any convenient known form.

The butt holder 8 accommodates the trigger mechanism, indicated generally by 10 in Figure 1. 55 Furthermore, the drawings show clearly that

The breech block guide 11 is of generally semi-circular hollow form in cross-section and is mounted within the gun body 3 for co-operation with a breech block 12 forming part of a breech action of the above defined dynamic type. The breech block 12 is also of semi-cylindrical form. It is substantially complementary to the said guide 11 and fits slidably the interior of the gun body when mounted therein on the breech block 10 guide 11.

The firing mechanism is mounted in the forward end of the breech block 12 (Figs. 2 and 3). In the illustrated embodiment of the invention the firing mechanism comprises a firing pin 13, mounted for axial movement in a vertical channel 15 in the forward end of the breech block 12 and biased by a spring 14 for movement in the rearward direction with respect to the breech block. A lever 15 is journalled for rocking movement on a pivot 16 in the said channel within the breech block, one end of said lever 15 engaging the rear-headed end of the firing pin 13 and the other end engaging the rear end of an actuating rod 17 also mounted for longitudinal sliding movement, in the axial direction, in the end of the breech block.

The forward end of the actuating rod 17 is arranged to make engagement with an abutment 18 provided in the gun body 3 as the breech block 12 approaches its forward position. The same abutment 18 also determines in combination with the stop face *a* of the breech block, the forward movement of the latter.

Whilst the breech block is in its open position as shown in Figures 1 and 2, the firing pin 13 is held by the spring 14 in its retracted position and, through the intermediary of the lever 15, maintains the actuating rod 17 in a position in which its fore end projects forwardly from the stop face *a* of the breech block 12.

As the breech block 12 approaches completion of its forward movement, the fore end of the actuating rod 17 strikes against the above-mentioned abutment 18 in the gun body 3 so that the actuating rod 17 is moved rearwardly relatively to the breech block, and by the engagement of the rear end of the rod 17 with the lever 15 the latter is caused to rock on its pivot 16 to, in turn, thrust the firing pin 13 forwards in the breech block to fire a cartridge in the firing chamber. It will be clear that the firing pin 13 cannot be actuated to fire the cartridge unless the breech block 12 has reached the exact position in which the firing is to take place.

the rod 17 can be easily removed from the breech block 12 upon removal of pin 16 and lever 15.

I claim:

1. A sub-machine gun of the dynamic type comprising in combination, a tubular gun body, a breech block axially slidable within the said body, a firing pin mounted for limited axial sliding movement in the forward portion of the said breech block, spring means urging said firing pin in a rearward direction, a double ended rockable lever pivoted between its ends in the forward part of said breech block and having one end freely engaging with the rear end of said firing pin for urging the latter forwardly, an easily replaceable actuating rod mounted, independently of said lever, for axial sliding movement in the forward portion of the said breech block and arranged to cooperate at its rear end with the other end of said lever, and an abutment upon the body of said gun arranged to engage, as the breech block approaches its final forward position, the forward end of the said actuating rod in order to slide the same rearwardly in the breech block for actuating the said rockable lever and firing pin.

2. A sub-machine gun of the dynamic type com-

prising in combination, a tubular gun body, a breech block axially slidable within said gun body, said gun body having at its forward part an abutment constituting a breech block stop and said breech block having at its front end a stop face co-operating with said abutment, a firing pin mounted for axial rectilinear sliding movement in the forward portion of the breech block, spring means urging said firing pin in a rearward direction, a double ended rockable lever pivoted between its ends in the forward part of the breech block and having one end freely engaging with the rear end of said firing pin, a displaceable actuating rod mounted in the front upper portion of the breech block for rectilinear sliding movement in a direction parallel to the movement of the said firing pin and having its rear end in engagement with the second end of said rockable lever, and having its front end arranged to project normally forwardly beyond the said stop face of the breech block and to engage the said abutment on the gun body as the breech block approaches its final forward position.
